UNITED STATES PATENT OFFICE.

THEODORE C. CHRISTENSEN, OF MENOMINEE, MICHIGAN.

REGISTER FOR FILING ACCOUNTS.

1,073,027.

Specification of Letters Patent.

Patented Sept. 9, 1913.

Application filed February 4, 1913. Serial No. 746,153.

To all whom it may concern:

Be it known that I, THEODORE C. CHRISTENSEN, a citizen of the United States, residing at Menominee, in the county of 5 Menominee and State of Michigan, have invented a new and useful Register for Filing Accounts, of which the following is a specification.

One object of the present invention is to 10 provide a filing or account register in which a single transversely movable lever may be positioned to raise the several leaves of the cabinet separately.

Another object of the invention is to provide 15 novel means for manipulating and controlling the movement of the lever whereby the leaves are actuated.

It is within the scope of the invention to improve generally and to increase the utility 20 of devices of that type to which the present invention appertains.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within 25 the scope of what is claimed, without departing from the spirit of the invention.

In the drawings:—Figure 1 shows the invention in perspective; Fig. 2 is a perspective of the leaf raising lever. Fig. 3 is a 35 perspective of the latch block; Fig. 4 is a sectional elevation of the latch block and the head whereby the latch block is supported; Fig. 5 is a vertical longitudinal section of the complete device; Fig. 6 is a sectional 40 detail of the leaf raising lever and its mounting. Fig. 7 is a perspective showing the indicator and attendant parts; and Fig. 8 is an elevation of a portion of the case.

In carrying out the invention there is provided a case 1, equipped in its interior with upper supports 2 and with lower supports 3, the supports 2 and 3 extending from one end of the case toward the other end thereof. The supports 2 and 3 are connected by up- 45 right rods 4.

The invention further includes a plurality of leaves 5 and of these leaves 5 there may be any number. The leaves 5 are equipped along their edges with bearings 6, receiving 50 the rods 4, to the end that the leaves 5 may be moved vertically. The leaves 5 normally

rest upon the lower supports 3. Each leaf 5 carries any desired number of bill holding clips 7 which may be of any form. In the present instance, each clip 7 is of arched 60 form and carries a name plate 8, the intersecting lower ends 9 of the clips being secured to the plate 5.

In one side wall of the case 1 there is a transverse slot 10 and projecting upwardly 65 into the slot 10 are teeth 11. Located upon the outside of the case 1 and below the slot 10 is a cleat 12.

A guide rod 17^a is located within the case and extends parallel to that wall of the 70 case which is provided with the slot 10. Mounted to slide upon the guide rod 17^a and to rotate thereon is a tubular bearing 17, and secured to one end of the tubular bearing 17 is a tubular head 100 carrying a 75 projecting arm 15 provided at its upper end with an enlargement 16.

An indicator 29 is provided, the same being in the form of a bar, having at its upper end an outstanding finger 31 adapted to 80 move along a series of characters 33 inscribed upon the upper edge of one wall of the case 1. The indicator 29 lies between one wall of the case and one of the upper supports 2, as will be understood best when 85 Fig. 5 is examined, the construction being such that when the tubular bearing 17 is rotated upon the guide rod 17^a, the finger 31 of the indicator 29 will be held upon the characters 33 by the said upper support 2. 90 In order that the tubular bearing 17 may rotate without swinging the indicator 29, any suitable mechanism may be provided. In the present instance, the lower end of the indicator 29 is equipped with a transverse 95 head 101 terminally engaged within the head 100, the head 100 being slotted as indicated at 102, so that the head 100 may rotate upon its axis, without swinging the indicator 29. If desired, one end of the transverse head 101 of the indicator 29 may be held beneath a removable plate 103 which is secured to the part 100. Secured to the opposite end of the tubular bearing 17 is a support 14, preferably taking the form of a 105 block, the support or block 14 being provided in its sides with slots 25. A latch block 19 is provided, the same being shown in detail in Fig. 3. The latch block lies in the slot 10 and is provided at its outer end 110 with a button 20 located outside of the case 1. The latch block 19 is provided, below

the button 20, with a hook-shaped latch 28 which is adapted to coöperate with the cleat 12 as shown in Fig. 5. The latch block 19 includes an extension 21 having ribs 22 which are slidably received within the support 14. A pin 24 outstands from the ribs 22 and is received in the slots 25 of the support 14, to aid in guiding the sliding movement of the latch block. In one end of the support 14 and in the corresponding end of the extension 21 of the latch block 19 there are coöoperating notches defining an opening 26 in which is located a retractile spring 27, one end of the spring 27 being secured to the cross pin 24 and the other end of the spring being secured to the support 14.

The operation of the device as hereinbefore described, is as follows:—When it is desired to elevate any one of the leaves 5, the button 20 is engaged by the hand of the operator, and the lever comprising the members 14, 17 and 15 is swung vertically upon the rod 17^a until the portion 16 of the arm 15 lies below the lower edges of the leaves 5. The lever is then slid longitudinally of the rod 17^a until the index finger 31 of the indicator 29 registers above the character 33 which is peculiar to the leaf 5 which is to be elevated. When the coöperation between the finger 31 and the appropriate character 33 indicates that the portion 16 of the arm 15 is beneath the proper leaf 5, the button 20 may be depressed, causing an elevation of the portion 16 of the arm 15, and causing an elevation of the selected leaf 5. When the button 20 is depressed to cause an elevation of the arm 15, the support 14 will register between certain of the teeth 11 and thus further sliding movement of the lever

will be prevented. At the same time, the latch block 19 is drawn outwardly, putting the spring 27 under tension. When the latch block 19 is released, the latch 28 will engage beneath the cleat 12, and thus a dropping of the arm 15 will be prevented, the selected leaf being held in an appropriate position. In order to lower the selected leaf, the latch block 19 is pulled outwardly, by means of the button 20, so that the latch 28 no longer is engaged beneath the cleat 12. Then, the tubular bearing 17 may be rotated on the rod 17^a to permit a lowering of the arm 15 and a lowering of the selected leaf 5.

Having thus described the invention, what is claimed is:—

In a device of the class described, a case; a plurality of individually movable leaves in the case; a support upheld by the case; a lever mounted on the support to slide thereon, thereby to position the inner end of the lever in operative relation to any leaf, the lever being mounted to swing with the support as a center; a latch movably mounted on the outer end of the lever; and means for receiving the latch to hold the lever against both sliding and swinging movement, the latch, when disengaged from said means, constituting means for sliding and swinging the lever.

In testimony that I claim the foregoing as my own, I have hereto affixed my signature in the presence of two witnesses.

THEODORE C. CHRISTENSEN.
